UNITED STATES PATENT OFFICE

2,575,239

REVERSIBLE BIT AND HOLDER THEREFOR

Robert J. Stephens, Montgomery, W. Va., assignor
to Marathon Coal Bit Company, Inc., Mont-
gomery, W. Va., a corporation of West Virginia

Application June 13, 1950, Serial No. 167,729

1 Claim. (Cl. 255—61)

1

This invention relates to certain new and useful improvements in reversible bits and holders therefor and has for its principal object the provision of an improved construction of this character which will be highly efficient in use and economical in manufacture.

An object of my invention is to provide a reversible bit and holder therefor of the character hereinafter more fully set forth, especially useful for drilling any hard formation including all formations of earth strata or any synthetic product. The bit and holder therefor are especially designed for use by the coal mining industry for drilling blast holes, steel pin timbering holes, hanger holes, and the like.

A further and equally important object of the invention is to provide a reversible bit having opposed cutting heads with two reaming sides common to both heads whereby the cutting heads and the reaming sides may be sharpened whenever found desirable and necessary.

Another object of the invention is to provide a bit holder in which there is an arrangement for permitting the passage therethrough of air or water to facilitate and expedite the drilling operation and to expel from the drilled hole the dust or like matter, brought about through the drilling operation.

Another object of the invention is to provide an attachment between the bit and the holder therefor whereby as the cutting head is reduced in size by reason of having been sharpened, the bit may be adjusted outwardly in a longitudinal direction from the holder.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a side elevational view showing the bit holder and bit embodying my invention;

Fig. 2 is an edge view of the same;

Fig. 3 is a perspective view of the bit embodying my invention;

Fig. 4 is an end view of the same;

Fig. 5 is a sectional detail view taken substantially on line 5—5 of Fig. 2; and

Fig. 6 is a sectional detail view taken substantially on line 6—6 of Fig. 2.

As hereinbefore stated, my improved bit and holder therefor is especially designed for use in the coal mining industry; however, the same may be used for drilling purposes other than in such industry.

2

To accomplish the several objects of my invention, I provide a holder H formed as an integral part of a shank 10. This shank 10 is adapted to be mounted in a suitable driving chuck (not shown). The head provides a transversely extending slot 11, the base of which is triangular in plan view as at 12, with the apex 13 thereof intersecting a longitudinal passage 14 formed in the shank 10, and having communicating therewith a plurality of branch passages 15.

Formed in the confronting fingers 16 of the holder H providing the slot 11, are aligned openings 17, one of which is provided with screw threads to receive the threaded end portion of

15 a clamping screw 18.

The bit embodying my invention is indicated at 19, and this bit provides oppositely disposed cutting heads 20 and 21 and reamer side edges 22 common to both heads. The cutting heads are 20 triangular in plan view to conform to the shape of the triangular section of the slot 11. These heads 20 and 21 provide cutting edges 23.

Formed in the bit 19 in parallel relation with respect to the reaming side edges 22 is an elongated slot 24 through which projects the threaded shank of the clamping bolt 18.

In use, the bit is positioned in the slot 11 between the fingers 16, with one of the cutting heads such as 21 (Fig. 5) positioned in the triangular shaped base of the slot 11, the walls of which base cooperate with the adjacent edges of the head 21 to prevent movement of the cutting bit about the clamping screw 18. After the bit has been positioned in the slot 11 in the manner shown in Fig. 5, the clamping screw is adjusted to bear the fingers 16 into clamping engagement upon the adjacent side walls of the bit, thereby to rigidly clamp the bit within the slot 11.

The elongated slot 24 permits the bit 19 to be moved outwardly whenever its projecting cutting head is reduced in size by sharpening operation. As the cutting heads 20 and 21 are of similar construction, it is clearly manifest that the bit may be reversed to interchange the heads in cutting position.

The reaming side edges 22 result in the production of a hole which is substantially uniform in diameter and eliminate what is known in the art as rifling action.

By providing the passage 14 and the branch passages 15, water may be forced into the hole during the drilling operation, thereby greatly facilitating such operation. On the other hand, air may be forced through these passages to remove the accumulated dust from the hole.

From the foregoing description, it will be

apparent that I have provided a combination bit and holder therefore which will be of great utility in the coal mining industry, the bit, by reason of its adjustability, having substantially great longevity as compared with bits which are now in commercial use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

A tool of the class described comprising a shank, a holder integral with the shank at one end thereof and providing opposite its integral connection with the shank a transversely extending slot opening at the opposite side edge portions of the holder and at the end thereof in a longitudinal direction with respect to the long axis of the shank, the base of said slot being substantially triangular in cross section throughout the entire width of the holder, a bit having oppositely disposed aligned cutting heads, either

of which cutting heads being insertable in the said slot and each being triangular in plan view to conform to the shape of the base of said slot, and means for detachably connecting the bit in an adjusted position within said slot with one of the heads thereof projecting into the base of said slot, said connecting means comprising a clamping screw threaded into said holder and projecting through an elongated slot formed in the bit, said slot extending in a direction longitudinally with respect to the long axis of the shank whereby said bit may be adjusted longitudinally with respect to said shank.

ROBERT J. STEPHENS.
